UNITED STATES PATENT OFFICE.

CHARLES E. LOCKE, OF HAVERHILL, MASSACHUSETTS.

SHOE-RACK.

1,374,592.

Specification of Letters Patent. Patented Apr. 12, 1921.

Application filed April 23, 1920. Serial No. 376,101.

To all whom it may concern:

Be it known that I, CHARLES E. LOCKE, a citizen of the United States, and a resident of Haverhill, county of Essex, State of Massachusetts, have invented an Improvement in Shoe-Racks, of which the following is a specification.

This invention relates to racks for holding shoes in shoe factories, while on the last.

10 The forms of shoe racks, in most general use, usually comprise a pair of end frames having shelves extending therebetween and arranged one over the other, said shelves usually being formed of doweling and frequently being covered with heavy paper or cardboard.

Such form of racks do not support many types of shoes in a satisfactory manner, as, for example women's high-heeled shoes, as 20 they are liable to tip over, so that they rub against each other, or rest on one side, and, as the uppers of shoes of this type are frequently made of material which is easily soiled, or defaced, damage to the upper, in 25 this way frequently occurs.

Shoe racks which are adapted to support shoes bottom up are advantageous in that dust is less liable to settle on the uppers, but, so far as I am aware, such racks have supported the shoes by direct engagement with 30 the upper, and such an arrangement is likely to cause damage to the upper in various ways.

It frequently happens that separate shoes 35 are removed from a rack for examination and are not returned to the place from which they were taken. Different lots of shoes thus become broken or mixed, causing difficulty and delay.

40 Racks constructed of doweling are expensive to manufacture, on account of the high cost of doweling, and they lack durability.

The object of my invention is to provide a 45 form of shoe rack which will securely hold shoes while on the last in an inverted position, without contact either with each other or the rack, so that danger that the uppers thereof will become soiled or damaged is reduced to a minimum; which will permit 50 the shoes to be readily placed in position on the rack and removed therefrom, and in which a separate place is provided for each shoe, so that, if a shoe is removed, the place to which it should be returned will be evident.

55 Other objects are to provide a form of

rack which is of less expensive construction and greater durability than the racks in general use and which, if required, may be constructed so that they may be readily 60 "knocked down" and stored in a relatively small space.

I accomplish these objects by the means shown in the accompanying drawings in 65 which:—

Figure 1 is an end elevation and

Fig. 2 is a side elevation of a shoe rack embodying my invention.

Fig. 3 is an enlarged detail sectional view of one of the last holding means.

Fig. 4 is a detail view of a slightly modified form of the invention.

According to my invention I provide a shoe rack of the usual dimensions as to height and width, the frame thereof comprising 75 four corner uprights *a*, each pair of end uprights being connected by a series of horizontal cross bars *b*, arranged at suitable distances apart from top to bottom, and corresponding in number to the desired number 80 of shoe supports, as hereinafter explained. The directly opposite uprights are mortised into base bars *c* to which the usual casters may be attached. These parts of the frame are all of wood strips of sufficient size to give 85 the required strength and rigidity and the joints are preferably mortised and suitably braced.

The cross bars *b*, at each end correspond in 90 number and position and a longitudinally extending bar *d* is set into, and secured at its ends in each corresponding pair of cross bars, providing a series of horizontal supporting bars, which extend the entire length of the rack. Said supporting bars are arranged at a short distance from the middle 95 of the cross bars in which they are held, in alternate, or staggered relation;—that is, each bar is arranged at one side or the other of the middle and the next bar above and below any particular bar is arranged at the 100 opposite side of the middle from that at which such bar is arranged, as shown in Fig. 1.

Each supporting bar is provided with a 105 series of suitably and equally spaced, parallel pins *e* which are set therein in position to extend obliquely upward therefrom at an angle of about 45° from the vertical, the exact angle not being essential, the pins on any 110 particular bar being inclined from the side nearest which the bar is located, so that they

extend across the middle plane of the rack, and the usual arrangement being such that each pin is intersected at or near the middle by the middle longitudinal vertical plane of the rack.

Each of said pins is similar in size and shape to the ordinary pin of a last jack, so that it will be received by the thimble of an ordinary shoe last. Said pins are, however, 10 preferably slightly tapered, so that they are of substantially less diameter at their ends than the internal diameter of the last thimble and of greater diameter than said internal diameter near the bar in which they are 15 held.

In use, a shoe, while on the last, is placed on the rack by merely placing the last on one of the pins, so that it depends therefrom in an oblique position, as shown in Fig. 1, 20 20 the shoe being placed thereon from the side toward which the pin, which receives it, extends.

On account of the alternating and staggered arrangement of the supporting bars, 25 and the last-receiving pins, every shoe on the rack may be removed or replaced, without interfering with, or touching any other shoe or any portion of the rack, and this may be done by a straight motion in line 30 with the pins.

The arrangement is such, that, when the shoe or last is also in position on one of the last holding pins, no portion thereof will extend beyond the side of the rack, 35 as indicated in Fig. 1, and, as the last will be held in a position in which its weight will cause the last thimble to be cramped on the pin, the shoe will be held from swinging by the frictional engagement of the last 40 with the pin, the force of this frictional engagement being increased by the wedging action of the pin, near its base, in the mouth of the thimble, as indicated in Fig. 3. The shoes will thus be prevented from swinging, 45 so as to rub against each other, when the rack is moved.

By having the pins *e* taper, so that they are of substantially less diameter, at their ends, than the last thimble, the lasts may be 50 placed thereon with greater facility.

It will be evident that the shoes are held in such a position that dust settling thereon will settle principally on the shoe bottom, where it will do no damage.

55 As each shoe has a definite place in which it is held, so that, if one is removed, the place to which it must be returned is evi-

dent, and, as shoes are usually made in lots of six pairs or multiples of six, by providing a place for exactly six pairs on each bar the lots may be easily kept together and are unlikely to become mixed up.

The construction shown in Figs. 1, 2 and 3 is for low cut shoes, in which case the supporting bars are offset from the middle by 60 only a short distance and the pins are only of a length, but slightly greater than that of an ordinary jack pin, but, if the rack is adapted for high shoes the pins will be made of sufficient length and arranged to 65 hold the shoes in a position in which the top edges of the uppers will be held out of contact with the bars, as shown in Fig. 4.

In such instance the supporting bars *d'* will, if necessary, be set close to the sides 75 of the rack, in alternate relation, as before described, and the pins *e* will be made correspondingly longer, and, usually, will be set at greater angle from the vertical than that shown in Fig. 1, so that the shoes will 80 be so held that their foreparts will not extend beyond the sides of the rack.

The difference between the construction for holding boots and for holding oxfords does not, therefore, differ substantially, and 85 it will be understood that other similar variations may be made which will be within the scope of my invention.

I claim—

A rack for supporting shoes while on the 90 last comprising a pair of upright end supports, a series of horizontally disposed bars mounted in said supports and arranged in vertically spaced relation alternately at opposite sides of the middle vertical plane of 95 the end supports, and a single series of equally spaced, parallel, last-supporting pins mounted in each bar, the pins of each series being somewhat inclined from the vertical toward the opposite side of the 100 rack from that to which the bar thereof is nearer, so that each pin of one bar is extended in a line which passes adjacent and beneath the bar next above it, each pin being constructed to enter the jack-pin receiving aperture of a last and being located at a distance from the next adjacent pin sufficient to hold the shoes on the lasts out of contact, in close proximity and in a 105 downwardly inclined, inverted position.

110 In testimony whereof I have signed my name to this specification.

CHARLES E. LOCKE.
